SLOT CUTTING DEVICE

Joseph G. Schotthofer, Detroit, Mich.

Application December 1, 1947, Serial No. 789,073

7 Claims. (Cl. 90—38)

1

This invention relates to a slot cutting device. The invention is particularly concerned with a hand operable slot cutting device in the form of an attachment, and is adapted for detachable connection with various metal working machines as an economical substitute for the expensive power-operated slotting machines used in the larger machine shops.

A primary object of the invention is to provide a hand operable slot cutting device which is adapted for detachable connection with the tool rest of a lathe or other metal working machine for the cutting of key seats and the like as occasion may demand such an operation on any particular piece of work.

A further object of the invention is to provide a hand operable slot cutting device including a reciprocable cylindrical tool carrying ram and operating connections for the ram constructed to prevent same from rotating on its axis, whereby the use of a cooperating key and slot for such purpose is avoided.

A still further object of the invention is to provide a hand operable slot cutting device which includes adjustable and lubricated parts for maximum efficiency in operation.

A still further object of the invention is to provide a hand operable slot cutting device which is relatively simple in construction and which accordingly is capable of manufacture at relatively low cost, thereby adapting it for economical use in small machine shops wherein the rather expensive power-operated slotting machines in many instances would be prohibitive.

Other objects and advantages of the invention will become apparent in the course of the following detailed description, taken in connection with the accompanying drawing wherein—

Figure 1 is a top plan view of the device in accordance with a preferred embodiment thereof, the operating lever being shown broken away.

Figure 2 is a side elevational view of the device, with the operating lever broken away.

Figure 3 is a transverse sectional view in the plane of line 3—3 on Figure 2.

Figure 4 is a top plan view of the supporting base in the device.

Figure 5 is a fragmental vertical sectional view in the planes of line 5—5 on Figure 1.

Figure 6 is a plan view of one of the bearing washers used in certain pivot joints.

Figure 7 is a plan view of one of the thrust washers used in the pivot joints.

Figure 8 is a diametrical sectional view of the

2

thrust washer in the plane of line 8—8 on Figure 7.

Figure 9 is a broken side elevational view of one of the bolts used in the pivot joints.

Figure 10 is a view of the bolt shown in Figure 9 as observed from the right thereof.

Figure 11 is a fragmentary longitudinal section on an enlarged scale and disclosing in particular the adjustable and releasable connection between the ram and tool bar.

Referring now in detail to the drawing, 10 designates a base which is provided with an elongated slot 11, and a split vertically disposed sleeve 12 is unitary with one end of the base. The sleeve is provided with lugs 13 at opposite sides of the split therein and a screw 14 is engaged in such lugs for contracting the sleeve.

The base 10 is adapted for disposition on a tool rest R of a lathe or other metal working machine, and the base is removably retained in position on the tool rest by means of a T-headed bolt 15, as is clearly shown in Figure 2.

The cylindrical vertical column 16 of a tubular body member 17 is vertically adjustably supported in the sleeve 12 as by means of the bolt 14.

The tubular body 17 is transversely slit a substantial distance from each end thereof, as indicated at 18. The slits extend through the wall of the body throughout an angular range of 180° and with the terminals of the slits disposed in vertical diameters of the body. The body is further longitudinally slit at 19, such slits being at the lower side of the body and extending from the free ends thereof to the slits 18. The slits 18 and 19 thus provide yieldable end portions 20, which are provided with lugs 21 on opposite sides of the slits 20, and screws 22 cooperate with the lugs for contracting the yieldable sleeve portions 19.

A split bushing 23, of bronze or the like, is disposed within each sleeve 19 and provides adjustable bearings for the opposite ends of a cylindrical ram 24 which is adapted for reciprocation in the body 17.

The forward end of the ram 24 is provided with an elongated cylindrical recess 25 which, at its forward end, opens through the free end of the ram and which is reduced toward its rear closed end in the provision of a shoulder 25'. The recess is adapted to removably and adjustably receive one end of a tool bar 26, and for the purpose of adjusting and retaining the tool bar in the recess the following structure is provided.

A block 27 is removably disposed within the recess and is retained in position against the

shoulder 25' by means of a set screw 27'. An adjustable stop in the form of a long screw 27'' is axially disposed within the recess and is threaded through a threaded aperture in the block 27. The rear end of the tool bar 26 bears against the outermost end of the screw for limiting movement of the tool bar within the recess, whereby a single tool bar of predetermined length may be used for different cutting jobs. The forward end of the screw is slotted as shown for adjusting same with a screw driver or the like, and the rear end of the screw is provided with a head 27^a which will abut the block 27 and prevent outward adjustment of the screw to an extent such that the tool bar has insufficient bearing in the recess. The recessed end of the ram is in fact a holding chuck and for this purpose the free end of the ram is beveled as indicated and threaded for the reception of a clamping nut 28, which also functions as a stop for limiting rearward movement of the ram in the body 17.

In order to provide for an effective gripping action of the recessed ram on the tool bar, the end of the ram is provided with a plurality of slots 24' which may preferably be four in number, as shown, and which extend a substantial distance from the extremity of the ram in the direction of its length, thereby providing yieldable segments between the slots for frictionally gripping the tool bar when the nut 28 is drawn up.

To effect an adjustment whereby to change the length of the tool bar externally of the ram, the nut 28 is loosened and the bar is removed, after which the accessible screw is adjusted by threading same one way or the other in the block 27. The tool bar is then re-inserted and the nut 28 drawn up.

A cutting tool 29 is removably seated in an aperture adjacent the free end of bar 26 and is retained in position by a screw 30.

A second stop collar 31 is provided for limiting forward movement of the ram in the body, and this collar is split and is secured to the ram rearwardly of the body by means of a screw 32.

From the above, it will be seen that the ram is slidably supported within the tubular body 17 in the absence of any means for restraining rotation of the ram about its axis.

It is, of course, essential that the ram have a rectilinear movement only and that it be restrained against rotation about its axis in order to provide a straight sided slot as effected by the cutter 28. While this rectilinear movement may be effected by the provision of the usual means in the form of a key and cooperating key way, such is subject to rapid wear, and as looseness develops between the key and key way, the ram is free for limited rotation about its axis, with the result that the cutting tool is given a wavy movement with a corresponding wall on the groove being cut.

In the present invention the ram is reciprocated by means of a link-and-lever structure having pivot joints of such form as to avoid rotation of the ram about its axis.

The operating means for the ram comprises a link 33 and a lever 34 having an actuating handle 35. The link is pivotally connected at one end thereof to the body 17 by means of a pivot joint 36, the link 33 and lever 34 being pivotally connected together by means of a pivot joint 37 and the lever 34 being pivoted intermediate its ends to the ram 24 by a pivot joint 38.

Each of the pivot joints comprises a thrust washer 39 and a pair of bearing washers 40. These washers are of relatively large diameter 75 on said body member adjacent the front end

and they all lie in horizontal planes in the assembled joints, the washers in the joints 36 and 37 being in common planes and those in joint 38 being in planes parallel with those containing the washers of joints 36 and 37.

Each of the joints includes a pivot bolt 41 and a cooperating clamp nut 42.

Each of the bolts has a relatively long smooth shank portion and is screw-threaded at its lower end only, and such screw-threaded end in joint 36 has screw-threaded engagement with a boss 43 on body 17, the screw-threaded end in joint 37 has screw-threaded engagement with lever 34, and the screw-threaded end in joint 38 has screw-threaded engagement with the flattened end portion 44 of ram 24.

The thrust washers 39 are uppermost in the joints and are each provided with an oil hole 46. The bearing washers 40 are disposed on opposite sides of link 33 in joints 36 and 37 and on opposite sides of lever 34 in joint 38, and each of these washers is provided with a plurality of oil-distributing holes 47.

Each thrust washer 39 is provided with a slot 48 in its upper face, and such slot has a downwardly and inwardly beveled side wall.

The head of each pivot bolt 41 is provided with opposite parallel tapered portions 49 which engage the beveled walls of slots 48 whereby relative rotation of the thrust washers and bolts about the axes thereof is prevented, for the reason that considerable wear would result if the relatively small bolt heads rotated relative to the thrust washers.

From the above, it will be seen that only the bearing washers 40 and the link or lever disposed therebetween have rotation relative to the bolt 41, and since the washers are of relatively large diameter and by means of the oil holes the contacting surfaces are well lubricated, little wear from friction can occur. The bolts 41 are drawn up to maintain the washers in firm engagement, whereby the link 33 and lever 34 are constrained to move in horizontal planes, and since the joint 38 is on the ram it is effectively restrained against rotation about its axis.

Should any play develop in the pivot joints, the bolts 41 may be tightened and the clamp nuts 42 drawn up to retain the adjustment.

Should the ram become loose in the body 17 the screws 22 may be tightened to draw the bushings 23 into firm bearing engagement with the ram.

It should be appreciated from the foregoing disclosure that a slot-cutting attachment is provided by the present invention which is extremely simple in construction, is readily attachable to the work rest of a metal-working machine, and which is provided with manually operating means which confine the tool-carrying ram to movement along its axis only.

While I have disclosed my invention in accordance with a single specific embodiment thereof, such is to be considered as illustrative only, and not restrictive, the scope of the invention being defined in the following claims.

What I claim and desire to secure by U. S. Letters Patent is:

1. A slot-cutting attachment comprising a base for removable connection with the tool rest of a metal-working machine, a horizontally disposed tubular body member disposed above the base and adjustably supported thereby, a cylindrical tool operating ram mounted in said body member for axial reciprocation therein, a boss 70 on said body member adjacent the front end

thereof, a flattened portion on said ram adjacent the rear end thereof, a horizontally disposed relatively wide link having one end thereof movably connected with said boss by a pivot joint, a horizontally disposed relatively wide lever movably connected intermediate its ends to said flattened portion of the ram by a pivot joint, and the link and lever being movably connected at adjacent ends thereof by a pivot joint.

2. The structure according to claim 1, together with adjustable bearings for said ram disposed adjacent opposite ends of said body member.

3. The structure according to claim 1, wherein said link is disposed above the body member and wherein said lever is disposed between the link and body member and is provided with an operating handle.

4. The structure according to claim 1, wherein the forward end of said ram is provided with a cylindrical recess, a cutting tool bar having one end thereof removably and adjustably disposed within said recess, an adjustable stop within the recess for limiting movement of the bar therewithin, and clamping means on the free end of the ram for frictionally retaining the bar in any adjusted position within the recess.

5. The structure according to claim 1, wherein each of said pivot joints comprises a vertically disposed bolt having the free end portion of its shank threaded and locked against rotation in one of the parts connected, the shank of the bolt between said threaded portion and the head thereof extending freely through another of the parts connected, a thrust washer beneath the head of the bolt and locked thereto to prevent relative rotation between the washer and bolt, and a bearing washer loosely surrounding the last-named shank portion and disposed on each side of the other part connected.

6. A manually operable slot-cutting device comprising a base for detachable connection with the tool rest of a metal working machine, a hori-

zontally disposed tubular body member supported by the base, a cutting tool operating ram disposed within the body member for reciprocatory movement, operating means for the ram comprising a horizontal link and a horizontal lever, a pivot joint connecting one end of the link with the body member, a pivot joint interconnecting the link and lever, and a pivot joint connecting the lever with the ram, said pivot joints each including a vertically disposed pivot bolt and a plurality of relatively large horizontally disposed washers for maintaining the link and lever in horizontal planes in operation and for preventing rotation of the ram about its axis.

7. A manually operable slot-cutting device comprising a base for detachable connection with the tool rest of a metal working machine, a horizontally disposed tubular body member supported by the base, a cutting tool operating ram disposed within the body member for reciprocatory movement, and manually operable means connected with the body member and the ram for reciprocating the latter, the said body member being supported by the base by means of a vertically disposed cylindrical column depending from the body member, an adjustable sleeve on the base receiving said column in adjusted positions thereof, and screw means for tightening the sleeve about the column in any adjusted position thereof.
